(57) **CLAIM**

The ornamental design for an ice cube tray as shown and described.

DESCRIPTION

FIG. 1 is an exploded top perspective view of an ice cube tray showing my new design;
FIG. 2 is an exploded bottom perspective view thereof;
FIG. 3 is an exploded front view thereof;
FIG. 4 is an exploded rear view thereof;
FIG. 5 is an exploded left view thereof;
FIG. 6 is an exploded right view thereof;
FIG. 7 is an exploded top view thereof;
FIG. 8 is an exploded bottom view thereof;
FIG. 9 is a perspective view of the ice cube tray where the ice cube tray is in a configuration of use; and,
FIG. 10 is a cross-sectional view of the ice cube tray taken along section line 10-10 in FIG. 7.
